LLOYD VAN HORN ARMSTRONG, OF UPPER MONTCLAIR, NEW JERSEY, ASSIGNOR TO INGERSOLL-RAND COMPANY, OF JERSEY CITY, NEW JERSEY, A CORPORATION OF NEW JERSEY

STEERING GEAR

Application filed August 2, 1928. Serial No. 297,033.

This invention relates to navigation, but more particularly to steering apparatus for seagoing vessels.

The object of the present invention is to 5 provide a power driven steering apparatus that utilizes what is commonly known as the "follow up" motion for imparting desired directions to the rudder of the craft.

A still further object of the invention is 10 to provide a power driven steering apparatus, that is fully and quickly responsive to operations of the steering control. Towards this end the invention contemplates a power driven steering control that may supersede 15 the conventional steering gear of an engine driven craft, while at the same time permitting the craft to be steered manually by the conventional apparatus if so desired.

With these and many other objects in view, 20 which will more readily be apparent as the nature of the invention is better understood, the same consists in the novel construction, combination, and arrangement of parts to be more fully described, illustrated and claimed.

25 One embodiment of the invention is shown in the accompanying two sheets of drawings in which:

Figure 1 is a side view partly in section of 30 a steering control apparatus manufactured in accordance with the present invention.

Figure 2 is a sectional view taken along the line 2-2 of Figure 1.

Figure 3 is a top plan view of the actual steering control,

35 Figures 4, 5 and 6 are plan views of the steering control and its operative connection with the valve of the steering motor. In these views, certain parts are broken away to more clearly reveal the nature of the invention, and also to render the same diagrammatic in their effect.

40 In each of the above mentioned views like characters of references are employed to designate like parts throughout, and the deck or support of the steering apparatus is designated at 10. Supported on a pair of standards 11 is the conventional barrel 12 to which is keyed the drum 13 carrying the rudder-head lines or chains 14 that lead over pulleys 15 to the tiller (not shown). The wheel is

shown at 16 and is secured in any suitable manner to the barrel 12. The above mentioned parts are purely conventional in design and no claim is made as to the novelty of the same which resides in the particular power driven mechanism for operating the conventional steering gear thus far described.

55 Secured to the deck 10 is a bracket 17, in which is mounted for rotation about a vertical axis, a central rod 18 having a bevel gear 19 keyed thereto at 20, and having a ratchet 21 secured adjacent its upper end. The upper end of this rod 18 is pivotally secured in a bracket 22, through which it extends, this bracket being secured to one of the standards 11. A small indicator 24 is squared on the shaft 18 above the bracket 22 and this indicator is adapted to register with graduations 25 on the bracket 22. A hollow rotatable shaft 26 surrounds a portion of the shaft 18 and this shaft has a lateral control lever 27 formed integral therewith, to which is pivoted a manually operated lever 29 carrying a pawl 21' which is a counterpart of the ratchet 21.

70 The lower end of the shaft 26 is provided with a lateral lug 30 having a downward extending pin 31 that extends into slots in a valve mechanism to be more fully described.

75 A reversible motor is designated at M and this motor may be operated by compressed air, steam, or any other fluid pressure. It is also within the scope of the present invention to operate this motor by electricity, if so desired. This motor has a valve chamber 32 offset with respect to the shaft 26 to accommodate a reversing valve (not shown) having a stem 33 thereon. This stem 33 has a lateral plate 34 formed integral therewith and in this plate are a plurality of slots 35 into which the pin 31 extends. While these slots may be formed in any suitable manner, it is preferable to form them as shown in Figs. 4, 5 and 6, there being a central slot 40 connected to a pair of curved branched slots 41 and 42, diverging from each other, and having curvatures substantially equal to the distance from the central shaft 18 to the pin 31. Thus it will be seen that as the shaft 26 is 80 rotated in one direction or the other, the 90 95 100

valve will be operated from a closed position to a reverse or forward operative position, or vice versa.

The barrel 12 is connected by a chain and sprocket mechanism 45, to a shaft 46, pivotally mounted in the bracket 17. This shaft has a bevel gear 19' meshing with the bevel gear 19. The motor shaft S is connected to the barrel 12 by a speed reduction chain and sprocket mechanism 48 as clearly shown in Fig. 1.

For the purpose of portraying the mode of operation of the device let it be assumed that the vessel is traveling an even course, if this is the case the parts are so adjusted that the control lever 27 and deflection indicator 24 are in register and the valve operating lug 30 is in its neutral position in the slot 40 so that the valve 32 is closed and the motor M is inoperative.

If it is desired to alter the course of the vessel, the pawl 21' is disengaged from the ratchet 21 and the control lever is shifted to a predetermined position, movement of this lever is transmitted through the shaft 26 to the lug 30 and pin 31, which travels into one or the other of the arcuate slots 41 or 42, thereby setting the reversible motor into operation.

Motion is then transmitted through the chain and sprocket mechanism 48 to the barrel 12 and drum 13. Motion is further transmitted from the barrel 12 through the chain and sprocket mechanism 45 to the shaft 46, through the medium of the bevel gear 19 and 19', return motion is imparted to the shaft 26, which is locked to the shaft 18 by the ratchet and pawl mechanism 21 and 21'. This motion commences instantaneously when the control lever 27 is first thrown from its neutral position and continues until such time as return motion of the shaft causes the pin 31 to enter the slot 40 to close the valve 32 and shut off the motor. Thus the device operates upon what is commonly known as the "follow up" motion, to alter the rudder's position. The helmsman can by intelligently calculating a predetermined throw to be given the control lever, automatically and instantly give the rudder of his vessel a predetermined angular setting.

It is apparent that a vessel under progress seldom travels a very great distance with its rudder set at an angle to its longitudinal axis. In practically every instance where the rudder is set at an angle, such a setting is only a temporary one and the rudder is normally given a set for the course of a few seconds and usually it is returned to its normal inoperative aligned position. When the vessel is being steered by the conventional wheel, such as is shown at 16, it is difficult for the helmsman to calculate the neutral position of his rudder. But in the present instance the visual means indicating the set of

the rudder will permit the operator to determine the temporary course of his vessel at all times. When the rudder is to be set in its neutral position from any other position, it is merely necessary to throw the control lever to such an angle that it comes into alignment with the indicator 24, and to thereby release the same. When this is done the valve is opened in a manner already described and the power mechanism is set into motion until such a time as both the control lever and the indicator again come into alignment automatically in their neutral position.

I claim as my invention:

1. The combination with a steering device having a barrel and rudder-head lines leading therefrom, of a reversible motor connected to the barrel to drive the same; a valve for said motor adapted to impart movement in either direction to said motor or to stop the same; means offset with respect to the valve and interlockingly engaged therewith for manually moving said valve from a closed position to an open position to render the motor operative for driving the barrel in either direction, and a connection between said barrel and said means, operable by either directional movement of the barrel to close the valve and render the motor inoperative.

2. The combination with a steering device having a barrel and rudder-head lines leading therefrom, of a reversible motor connected to said barrel for rotating the same; a rotatable valve for starting and imparting movement in either direction to said motor; said valve having a lateral plate thereon adapted to be moved to operate the valve; a slot in said plate and a manually operated shaft having an offset pin extending into said slot for moving said plate to operate the valve; a second shaft having a manually releasable connection with said first shaft; means operatively connecting said second shaft to said barrel, whereby movement of said first mentioned shaft will be transmitted through said means to said second shaft and through said releasable connection to return said first mentioned shaft to its original position, and close said valve.

3. The combination with a steering device having a barrel and rudder-head lines leading therefrom, of a reversible motor connected to said barrel for rotating the same; a rotatable valve for starting, and imparting movement in either direction to said motor; said valve having a lateral plate thereon adapted to be moved to operate the valve; a plurality of interconnected slots in said plate; a manually operated shaft having an offset pin extending into said slots for moving said plate to operate the valve to start said motor in either direction or to stop the same; a second shaft having a manually releasable connection with said first shaft; and means operatively connecting said second shaft to said

barrel, whereby movement of said first mentioned shaft setting said motor and barrel into operation will be transmitted through said means to said second shaft and through said releasable connection to return said first mentioned shaft to its original position and close said valve.

4. A follow up control apparatus for imparting predetermined angular movements to a driven shaft, of a power shaft connected to said driven shaft and a reversible motor for driving the same, a manually operative rotary valve for said motor adapted to control the directional movements of the same; a plate on said valve having a slot therein and means slidable in said slot responsive to minute directional movements of the driven shaft for automatically closing the valve.

In testimony whereof I have signed this
specification.

LLOYD VAN HORN ARMSTRONG.
